(57) **CLAIM**

The ornamental design for A mobile information terminal, as shown and described.

DESCRIPTION

FIG. 1 is a bottom, front and right side perspective view a mobile information terminal showing our new design,

FIG. 2 is a bottom, front and right side perspective view of the mobile information terminal in an in-use position;

FIG. 3 is a front elevational view thereof,

FIG. 4 is a rear elevational view thereof,

FIG. 5 is a left side elevational view thereof,

FIG. 6 is a right side elevational view thereof,

FIG. 7 is a top plan view thereof,

FIG. 8 is a bottom plan view thereof,

FIG. 9 is a front elevational view with the keyboard shown in an in-use position;

FIG. 10 is a bottom plan view thereof; and,

FIG. 11 is a right side elevational view thereof.

The broken lines shown in the drawings are for the purpose of illustrating unclaimed portions of the mobile information terminal and form no part of the claimed design.

1 Claim, 5 Drawing Sheets
